NUT LOCK

George R. Micuta, Bridgeport, Conn.

Application September 28, 1945, Serial No. 619,151

4 Claims. (Cl. 151—25)

1

This invention relates to nut locks, and has for one of its objects to improve generally upon devices of this character so as to simplify and make more practical the structure and at the same time increase the efficiency of such devices without detracting from the strength and durability thereof. In my U. S. Patent No. 2,427,684 of September 23, 1947, there is disclosed and claimed a similar nut lock. This patent was application No. 598,948, filed June 12, 1945.

Another object is to provide for the application of the locking element to any standard form and kind of nut body.

A further object is to provide means on the nut body for holding the locking device in either locking or unlocking position.

A still further object is to attain the effect of a predeterminable locking force by the use of locking elements whose spring tension under given conditions is known.

Yet another object is to secure a predeterminable locking force by the provision of lugs whose shoulders, which retain the locking element in its locking and unlocking positions, will determine the amount of distortion or tension which the locking element will undergo in the locking operation.

Still another object is to provide predeterminable locking forces measured and determined with torsion wrenches or other instruments and thus permit of standardization of such devices in the nut lock field.

Other objects and advantages to be attained will hereinafter more fully appear in the following description.

An illustrative but non-limiting embodiment of the invention is illustrated in the accompanying drawings, in which:

Figure 1 is an end elevation of the nut provided according to the invention and applied to a bolt with the locking element in locking position;

Figure 2 is a view in section of the nut body and side elevation of the screw threaded end portion of the bolt with the locking element in locking position;

Figure 3 is a side elevational view of the parts shown in Figure 2;

Figure 4 is a view similar to Figure 3, but showing the locking element in unlocking position;

Figure 5 is a view similar to Figure 1 of a modified construction of the nut body to accommodate the locking element of the present invention;

2

Figure 6 is a side elevational view;

Figure 7 is a side elevational view taken at right angles to the showing in Figure 6;

Figure 8 is a fragmentary end elevation illustrating the locking element in its normally set condition and in unlocking position on the nut body.

Figure 9 is an end view showing another modification of the nut structure and locking device;

Figure 10 is a side elevation of the parts shown in Figure 9;

Figure 11 is a view taken at right angles to the showing in Figure 10;

Figure 12 is an end view of still another modified construction and arrangement;

Figure 13 is a sectional view of the assembly shown in Figure 12; and

Figure 14 is a side elevational view at right angles to the showing in Figure 13.

Referring now to the drawings in detail, the numeral 10 designates the plain cylindrical body portion of a conventional bolt or the like, the same having the screw threaded end portion 11. Placed on the screw threaded portion 11 of the bolt is a nut 12 of conventional form except as to provision thereon for the application of the locking device of the present invention.

As above stated, the nut body 12 may be of any conventional form. As shown in the several hereinafter described modifications, it is of the hexagonal type. The only change in the nut body structure is the provision of an upstanding lug or lugs, placed so as to give the greatest utility under the conditions for which the nut lock is proposed and to permit the greatest ease of manufacture. In Figures 1 to 4 there is shown a single elongated lug 13 extending along and slightly inward and adjacent one of the polygonal sides of the outer end face of the nut body 12. The opposite ends of this lug 13 are stepped and slightly recessed, as at 14 and 15, the recesses 14 being the higher ones and the recesses 15 being the lower ones, and the distance between the higher recesses 14 being narrower than the distance between the lower recesses 15.

The locking element 16 of the present invention in all modifications, is of a bowed or semi-looped form. In Figures 1 to 4 it is semi-circular or substantially crescent-shaped, and it is made of metal possessing substantial inherent resiliency whereby the same is form-retentive and reactive with a tendency to assume its original form after it has been expanded or deformed when it is applied in use, as will presently more fully appear.

As shown more clearly in Figures 3 and 7, the

locking element 16 may be of circular cross section. However, as far as the inventive idea is concerned this cross section may be varied in different adaptations of the invention.

Normally, the locking element 16 is of a set form so that it is slightly expanded when its opposite end portions are engaged with the outer, closer associated, slightly recessed shoulders 14 so that the reactive effect of the element 16 is to clamp and hold upon the shouldered portions 14. This engagement of the element 16 with the shoulders 14 is in the unlocking position of the element, in which position the element is diagonally disposed, as indicated in Figure 4, in which position its curved middle portion 17 is entered in between the valley of the contiguous threaded portion 11 of the bolt, but not with binding effect. In this position of the locking element, its middle portion 17 has but slight frictional engagement with the threaded portion of the bolt so that the nut may be turned freely on the threaded portion of the bolt.

To set the locking element 16 in locking position, its opposite outer end portions are forced downwardly from the outer pair of recessed shoulders 14 and onto the lower pair of recessed shoulders 15 at the ends of the lug 13. This spreads the end portions of the element 16 under tension and at the same time the effect is to force the middle portion 17 into tight contact in the valley of the threaded portion of the bolt with such holding effect that the nut cannot be turned on the threaded portion of the bolt except under very high applied force, and if such force is applied, mutilation of the threads of the bolt is liable to occur or the locking element 16 become broken. The holding effect of the locking element 16 is at least sufficiently effective to hold the nut against movement by vibration or shock.

To apply the locking element is but an easy matter, not only in the initial spreading of the end portions of the element to engage the outer shouldered portions 14 of the lug 13, but also in forcing the element inwardly into its further expanded and final locking position. This may be accomplished, obviously, by hand or by the application of a suitable implement to force the locking element into place. By the same token, the element 16 is as readily removed.

It is preferable to provide the outer ends of the portions of the element 16 which engage the lug 13 of the nut body with practical means of any suitable form and arrangement to assist in the manipulation of the element and to function effectively to prevent unintentional displacement of the element from its selectively set position, either locking or unlocking. As shown, the element is provided with inwardly projected lugs 18 and the ends of the element 16 are extended sufficiently to provide ample clearance spaces 19 between said lugs 18 and the adjacent outer end face portions of the lug 13 of the nut body. This space provision 19 is to facilitate the attachment of the locking element to the end portions 14 and 15 of the nut body lug 13 and also to allow for the contraction and expansion of the element 16 and to accommodate its tendency to slide bodily inward so that its middle portion 17 frictionally engages the threaded portion of the bolt with ample holding effect.

While in some adaptations of the invention the lug 13 may be applied as a protrusion upon the outer end face of the nut body, as shown in Figures 1 to 4, inclusive, it is noted that the end face portion of the nut body 12 may be recessed, as at

20, and the lug 13' provided near the outer margin of said recess 20. In other respects, the nut body structure is the same as illustrated in Figures 1 to 4, inclusive, that is to say, the lug 13' is provided with the corresponding end recessed shouldered portions 14' and 15' which are identical with the corresponding parts 14 and 15 previously described.

It is clearly apparent that the two structural modifications illustrated in the drawings are substantially identical in the application of the invention, that is to say, as to the form of the locking element and its application to the nut body in engagement with the threaded portion of a bolt or the like, except that in the one case the retaining lug portion 13 is projected from the normal outer face portion of the nut body, whereas, in the other modification the recess 20 is provided in the nut body for the accommodation of the locking element 16 and the corresponding lug portion 13' which is otherwise identical with the aforesaid lug portion 13, is provided near the outer margin of the recess 20.

In Figures 9, 10 and 11 a further structural modification is shown somewhat along the general lines of the aforesaid adaptations of the invention as illustrated in Figures 1 to 8, inclusive, and particularly as to the form of the locking element 16. That is to say, the locking element 30 illustrated in Figure 1 and through Figure 11 is, in each instance, of semi-circular or arcuately bowed form. The only difference in the present, above noted structure, is that, instead of the elongated continuous lug 13 or 13', as the case 35 may be, a pair of separate spaced-apart narrow studs or lugs 21 are provided on the outer end of the nut body 12 adjacent the edge of the corresponding polygonal face of the body. Each of the studs or lugs 21 is stepped at its outer side and 40 slightly notched, as at 14' and 15', in the same manner as the aforesaid stepping and notching 14, 15, 14' and 15' of the respective elongated continuous lugs 13 and 13'. Otherwise, the application 45 of the locking element 16 to the nut body 12 is identically the same as in the first two herein illustrated and described structural modifications.

A still further modification is illustrated in Figures 12, 13 and 14. In this modification, the outer end of the nut body 12 is recessed, as at 20', somewhat similarly to the recessing 20 of the structure shown in Figures 5, 6 and 7, but more or less circularly and opened narrowly instead of being opened widely adjacent the margin of the nut body. Also, in this mentioned modification, 55 a single stud or lug 22 is provided at the end of the nut body 12, adjacent the edge of the corresponding polygonal face of the body and at the middle of the recess 20', instead of the aforesaid lugs 13, 13' and 21. This stud or lug 22 has a flat outer face 23 throughout from its base to its top, and the body of the stud or lug is of a substantially semi-circular cross section from top to base, except that its lower portion is of larger diameter, as at 24, and its upper portion 25 is of smaller diameter. In other words, the stud or lug 22 is stepped, except at its plain flat outer face, so as to have substantially the same effect on the resilient locking element as does the stepped end formation of the aforesaid lugs 13 and 13' and the later described studs or lugs 21. That is to say, 65 as to the control of the spreading and contraction of the locking element and its holding effect when applied in use. In this last mentioned modification the locking element 16' is of a substantially V-shape, having a rounded instead of

an abrupt pointed apex portion 17' intermediate its inclined leg portions to engage the threads of the bolt 10 similarly as does the intermediate portion 17 of the curved or arcuately bowed element 16. Except as to its difference in shape, the V-shaped element 16' functions substantially like the element 16 and, of course, except as to the difference in the form of the stud or lug 22 from the aforesaid lugs 13, 13' and 21. Specifically stated, before the locking element 16' is set in locking position when it is spread and engaged with the larger lower portion of the stud or lug 22 as shown in Figures 12, 13 and 14, it is placed at an inclined position, substantially as shown in Figure 4, and at the time is contracted slightly and in engagement with smaller upper portion of the stud or lug 22. It is then forced and sprung into its locking position.

As shown, the ends of the legs of the V-shaped element 16' are turned inwardly, as at 18, like the corresponding parts of the elements 16. In this connection, it is here noted that the end formations of the elements 16 and 16' may be varied from the particular form shown, and in some modifications the end portions of the elements may be plain and without any especial formation.

It is further noted that while several different adaptations of the invention are illustrated in the drawings, other modifications are contemplated within the purview of the invention as defined by the appended claims. This invention, therefore, is not limited to the specific constructions and arrangements shown.

Having thus described the invention, what is claimed is:

1. A nut lock wherein the nut body proper is provided with an upstanding lug on an end thereof, and a semi-looped locking element possessing certain inherent resiliency whereby to be spread under tension with its end portions in engagement with the ends of the lug projection on the nut body and with reactive effect whereby to urge the locking element with its intermediate portion in engagement with the threaded portion of the element to which said body is applied.

2. A nut lock provision as set forth in claim 1, wherein the opposite ends of the upstanding lug on the nut body are respectively formed with

stepped shouldered portions, the lineal distance between the outermost stepped portions being narrower than the distance between the innermost stepped portions, whereby the locking element may be engaged and frictionally held by the outermost stepped end portions of the nut body lug without locking effect upon the element upon which the nut is applied, but by movement of the locking element into engagement with the lowermost shouldered portions of the nut body lug the locking element is further tensioned and with reactive effect whereby to urge the locking element with its intermediate portion into engagement with the element to which the nut is applied.

3. A nut locking provision wherein the nut body is provided with an upstanding lug at the outer end thereof adjacent the side margin of the nut body, and a resilient semi-looped locking element having inwardly projected lugs at its opposite ends, said resilient locking element being spreadable under tension in frictional engagement with the adjacent end of the lug on the nut body with reactive effect to cause lineal movement of the end portions of the locking element transversely of the end portions of the nut body lug whereby to urge the intermediate portion of the locking element into engagement with the threaded portion of the element to which the nut is applied, the extreme end portions of the locking element having the inturned lug extensions being projected with the lug portions in spaced relation to the outer face of the nut body lug.

4. A nut lock provision as set forth in claim 3, wherein the opposite end portions of the nut body lug are stepped so as to receive and hold the locking element in both its originally expanded and ineffective locking position and in its further expanded and locking position.

GEORGE R. MICUTA.
